Inventor:

Heinrich Vollmer

UNITED STATES PATENT OFFICE.

HEINRICH VOLLMER, OF BIBERACH, GERMANY.

CARTRIDGE-FEEDING DEVICE.

1,413,694.

Specification of Letters Patent. Patented Apr. 25, 1922.

Application filed July 20, 1920; Serial No. 397,803.

To all whom it may concern:

Be it known that I, HEINRICH VOLLMER, a citizen of the German Empire, residing at Biberach, Germany, have invented certain new and useful Improvements in Cartridge-Feeding Devices, (for which I have filed application in Germany on April 1, 1913,) of which the following is a specification.

The present invention refers to a novel cartridge feed for machine and automatic guns of all descriptions which differs from the feeding devices hitherto employed by the simple and yet especially effective manner of feeding the cartridges into the barrel.

15 This is effected according to the present invention by means of a conveyor spiral formed substantially like a coil spring and consisting of wire, sheet metal strips or the like and rotatively disposed within a suitable channel or groove.

This conveyor spiral may be caused to rotate either by the recoiling breech-piece or by gas pressure or by a spring or else by some suitable motive force and, if desired, even by hand, suitable intermediate members serving to transmit the movement.

In the drawings affixed to this specification and forming part thereof, a cartridge feed according to the present invention is 30 illustrated by way of example. In the drawings—

Fig. 1 is a longitudinal section, showing the novel cartridge feed combined with a cartridge receptacle of peculiar form.

35 Fig. 2 is a plan view. Referring to the drawings, *d* is the conveyor spiral which is formed in the present instance of a piece of wire wound after the manner of a coil spring. One end of the spiral is rigidly fixed to the driving shaft *c*. The spiral is 40 rotatively disposed in the open channel *b* of semi-circular section which is shown in the drawing as being applied to the feed opening of some fire arm *a*. The channel *b* is preferably connected with a frame, adapted to be applied to the weapon and provided with two parallel ledges *g* serving for taking up and holding the removable cartridge receptacle *h*. The receptacle 45 aforesaid consists of a sheet metal casing

closed on all sides and having semicircular side walls distanced apart for the length of the cartridge *p* so that the cartridges accumulated therein can freely move relatively to each other.

55 The bottom of the cartridge receptacle has a broad slot therein and the receptacle is fixed between the ledges *g* aforesaid in such a manner, that the conveyor spiral projects through it into the receptacle, the 60 side walls of the receptacle extending beyond its bottom in order to secure a more perfect fixation in the frame. The semi-cylindrical cover of the wall does not extend quite down to the bottom but leaves 65 an opening *o*, allowing the cartridges to be introduced into the receptacle and to escape therethrough.

After the receptacle has been filled with cartridges, the opening *o* may be closed by 70 means of the slide *i* or the like, which may be turned upwards whenever cartridges shall be supplied. A pin *e* fixed in the centre of the semi-cylindrical receptacle near its bottom carries a partition loosely mounted 75 thereon and further a powerful spring *f* acting upon that partition and causing it to press the cartridges *p* towards the slot.

The upper half of the conveyor *d* projects into this slot and its windings are 80 distanced apart in such a manner as to be able to receive each one cartridge. On the spiral being set rotating, the row of cartridges gripped by the windings of the spiral will wander in the direction towards 85 the feed opening of the firearm and will be fed into it, one after the other.

The receptacle *h* shown by way of example might of course be replaced by some other suitable receptacle such as for instance 90 a prismatic container provided with a sliding bottom and having the cartridges disposed in vertical rows, which may be separated by vertical partitions.

After the last cartridge has left the receptacle, this latter may be replaced by a fresh one.

I claim:

1. In a gun feed device of the kind described in combination, a channelled frame, 100

wire spiral rotatively disposed in the channel and means for supplying said spiral from above with cartridges disposed transversely thereto.

2. In a gun feed device of the kind described in combination, a conveyor spiral and a semi-cylindrical cartridge receptacle

removably arranged on top of said spiral, a slot in the bottom of said receptacle and a spring actuated partition within said receptacle for forcing the cartridges contained therein towards said spiral. 10

In testimony whereof I affix my signature.
HEINRICH VOLLMER.
